ADJUSTABLE-CURVATURE EXPANDER
ROLL AND THE LIKE

John D. Robertson, Taunton, Mass.

Application May 23, 1952, Serial No. 289,524

15 Claims. (Cl. 26—63)

1

This invention relates to improvements in curved expander rolls for flexible sheet material. More especially it provides improvements in curved expander rolls which have provision for increasing and decreasing the amount of curvature in any particular roll to suit particular needs or requirements.

Curved expander rolls ordinarily are mounted with their opposite ends adjustably clamped so that the curved longitudinal axis of the roll may be selectively set in any of various planes. They have utility for spreading travelling sheets of fabric, paper, foils, films, and the like, and for removing wrinkles therein as any such sheet comes to the roll at its concave side and leaves the roll at its convex side on a course leading to or from any of various processing devices. The rolls also may be used for reducing the width of travelling sheets, as in the manufacture of creped sheet materials, for example, in which case the sheets would be led to the curved rolls at their convex sides and would leave the rolls at their concave sides.

Longitudinally curved rolls have additional utility for correcting bow of the weft or filler elements of woven sheet materials. Heretofore, bow-correcting rolls having a fixed amount of curvature have been arranged in pairs and mounted for swinging, each about a straight axis, with the rolls of each pair adapted to be swung bodily in opposite directions to increase or decrease the bow-correcting effect of the curved rolls on a travelling woven sheet engaging therewith. The invention may be employed, if desired, for varying the curvature of such bow-correcting rolls, as well as for varying the curvature of curved expander rolls.

In my Patent No. 2,547,975, dated April 10, 1951, there is disclosed a curved expander roll the opposite end portions of which are straight and only the central portion of which has variable curvature. My present invention goes beyond the disclosure of my said patent in that rolls according to my present invention may have variable curvature extending from end to end thereof, or may have straight central portions and variable curvature end portions, or straight end portions and variable curvature central portions. Also, the rolls as herein disclosed are more readily adjustable to attain a desired bow or curvature, as compared with the roll of my said patent.

It is among the objects of my present invention to provide rolls which may be employed as straight-axis rolls but each quickly and easily

2

may be provided with adjustable curvature which, in one embodiment, may extend from end to end of a roll or, in other embodiments, may be confined to either or both a central portion and opposite end portions of a roll. According to the invention, each roll has an axle which is resiliently flexible throughout one or more substantial portions of the length of the roll. The body of the roll is rotatable on the axle, and the axle may be locked in a condition in which it constitutes a straight axle of a straight roll, and also may be bowed and locked to provide longitudinal curvature at one or more predetermined portions of its length, or throughout its length, with provision whereby the curvature may be varied to suit particular requirements or desires, the roll body being self-adapting to any particular straight or curved condition of the roll axis, or portions thereof.

Another object of my present invention is to provide a roll having a flexible axle upon which the body of the roll is rotatable, and having means at an end portion of the axle, or at both end portions of the axle, for effecting a bowing of the axle at one or more predetermined substantial portions of the length of the roll, the said roll body comprising a series of roll sections and a flexible surface sleeve tying all of the roll sections together for rotation in unison with the surface sleeve about the axis of the roll axle regardless of the condition of the said axis as regards straightness or degree of curvature at particular portions thereof. The said roll sections are maintained in spaced relation by inter-engaging spacer elements which are self-adjusting as bowing of the roll axle proceeds, there being clamping means coacting with said bowing means rigidly clamping the spacer elements under endwise compression to maintain the roll with any selected condition of bow therein.

It is, moreover, my purpose and object generally to improve the structure and utility of rolls and especially of rolls having provision for imparting varying amounts of longitudinal curvature thereto, such as curved expander rolls and curved bow-correcting rolls as employed in the processing of travelling sheet materials.

In the accompanying drawings:

Fig. 1 is a plan view of a curved expander roll embodying features of the invention, portions of the roll being broken away;

Fig. 2 is a medial cross-sectional view through the roll and end clamps of Fig. 1, but with the longitudinal axis of the roll straight, and with

the roll axle rotated in the end clamps through 90° from its position in Fig. 1.

Fig. 3 is a medial cross-sectional view of the left-hand end portion of the roll of Fig. 2, on a larger scale, showing the roll and clamp after curvature has been imparted to the roll;

Fig. 4 is a cross-sectional view on line 4—4 of Fig. 2;

Fig. 5 is a cross-sectional view on line 5—5 of Fig. 2;

Fig. 6 is a cross-sectional view on line 6—6 of Fig. 2;

Fig. 7 is a top plan view of the bifurcated member of Figs. 2 and 3 to which the upper leaf of the axle is rigidly secured at the left-hand end of the axle of Figs. 2 and 3, its enclosing sleeve being shown in cross-section;

Fig. 8 is a medial cross-sectional view of the opposite end portions of a mounted adjustable-curvature roll having a modified form of axle construction, the main extent of the curved portion of the roll being broken away; and

Fig. 9 is a medial cross-sectional view of another modification showing only one end portion and a central portion of a roll both ends of which are identical.

Referring to the drawings, a longitudinally curved roll is indicated generally at 10 in Fig. 1, mounted in end clamps 12, 14 which have set screws 16 for securing the roll with its curved axis in a selected plane. When the set screws 16 are loosened, the roll may be adjusted in the end clamps 12, 14, about a straight axis common to both clamps, to place the curved axis of the roll in a desired plane, after which the set screws 16 may be tightened to secure the roll with its curved axis in the selected plane.

According to the invention, the roll 10 has a resiliently flexible axle comprising a stack of long resiliently flexible strips or leaves 18, 19, 20, 21, 22, 23, 24, 25, 26, preferably of metal, which together constitute a long leaf-spring on and along which a series of generally cylindrical roll sections 28, 30 are arranged, with suitable anti-friction bearing units, such as the ball-bearing units 32, intervening between the leaf-spring axle and each of the roll sections 28, 30, as best illustrated in Figs. 2 and 3 wherein the roll axle is shown rotated in the end clamps through 90° from its position of Fig. 1. A flexible surface sleeve 34, of rubber or the like, is engaged over the roll sections 28, 30, tying all of the roll sections together for rotation in unison with the surface sleeve 34, and bridging the spaces between adjacent roll sections.

The illustrated ball-bearing units 32 are of a type having an inner race 32^a and an outer race 32^b. The leaves of the leaf-spring axle have varying widths as best seen in Figs. 5 and 6, and they are stacked to provide a generally hexagonal composite cross-section. The inner race 32^a of each ball-bearing unit 32 has a hexagonal hole 36 therethrough whereby the ball-bearing units may be slidably and non-rotatably distributed along the leaf-spring axle, with annular spacing elements 38 predeterminedly arranged on the axle, followed by a second ball-bearing unit 32 with its roll section 28 thereon. After each subsequent ball-bearing unit is slid to its place on the axle, two of the annular spacing elements 38 intervene between it and the next unit 32 until all of the ball-bearing units are on the straight, leaf-spring axle. As shown, each of the roll sections 28 has an annular flange 29 thereon, and the roll sections are arranged with the flanges 29 at the left-hand ends of the roll

All of the leaves of the leaf-spring axle are rigidly secured together at one end of the leaf-spring, herein shown as the right-hand end as represented in Fig. 2, the leaves being welded or brazed together at the blackened edge portions 40 in the cross-sectional view of Fig. 5, and the end portions of the leaves being rigidly secured together to provide the relatively solid and rigid projecting end portion 42. This rigid end portion 42 of the axle has circular cross-section and is exteriorly threaded for a purpose which later will appear. All of the leaves are shown welded together at 43 throughout the extent of end portion 42 in Fig. 2.

At the other end of the leaf-spring, the top leaf 18 and the bottom leaf 26 project substantially outward beyond the ends of the intervening leaves 19, 20, 21, 22, 23, 24 and 25, and the projecting end of leaf 18 is rigidly secured to the cross-sectionally round rod or plunger 44 which is slidably mounted within a member 46. Member 46 is rigidly secured, as by welding at 47, within the relatively long tube or sleeve 48. The inner end portion of member 46 is bifurcated at 50, as best seen in Fig. 7, and the rod or plunger 44 has bearing support on and between the furcations 46^a, 46^b of member 46, as best seen in Fig. 4. The projecting portions of leaves 18, 26 have substantial extent between the furcations 46^a, 46^b, the leaf 18 being rigidly secured to the rod or plunger 44 as by being welded thereto at 45, and the leaf 26 being rigidly secured to the furcations 46^a, 46^b of member 46 as by being welded thereto at 49.

The rod or plunger 44 extends from its securement to leaf 18 outward within member 46 toward the outer end of the latter but terminates a substantial distance short of the said outer end of member 46. A screw 52 is threaded into the outer end portion of member 46 with its inner end engaging the outer end of rod or plunger 44, whereby the rod or plunger 44 may be forced inward along member 46 by inward screwing of screw 52, and the resilience of leaf 18 urges rod or plunger 44 outward along member 46 in response to outward screwing of screw 52. A locking screw 54 extends loosely through the screw 52 and has its end threaded into the outer end portion of rod or plunger 44, for securely locking the latter in any position along member 46 to which it may have been moved in response to turning of screw 52.

When the elements of roll 10 are being assembled, the leaf-spring axle will be substantially straight as in Fig. 2, and free of the end clamps 12, 14. The ball-bearing unit 32 at the left-hand end of the roll, with its roll section 28 thereon, is first arranged over the right-hand end of the axle and slid to its position of Fig. 2 in which its inner race 32^a is stopped against the inner end of the tube or sleeve 48. The roll section 28 on this unit 32 has an annular flange 29 thereon, and an end plate 56 preferably is secured to flange 29, as at 29^a. Two of the annular spacing elements 38 next are loosely arranged on the axle, followed by a second ball-bearing unit 32 with its roll section 28 thereon. After each subsequent ball-bearing unit is slid to its place on the axle, two of the annular spacing elements 38 intervene between it and the next unit 32 until all of the ball-bearing units are on the straight, leaf-spring axle. As shown, each of the roll sections 28 has an annular flange 29 thereon, and the roll sections are arranged with the flanges 29 at the left-hand ends of the roll

sections which are to the left of the center of the roll in Fig. 2, and with the flanges 29 at the right-hand ends of the roll sections which are to the right of the center of the roll in Fig. 2. The roll section 30 at the center of the roll has no flange.

When all of the roll sections 28, 30 are distributed along the leaf-spring axle, the resiliently flexible surface sleeve 34 is expanded and slid to its position over all of the roll sections, in a conventional manner, following which the end plate 56 for the right-hand end of the roll will be secured to the flange 29 of the end-most roll sections 28, as at 29a.

Before the right-hand end of the roll axle (Fig. 2) is inserted in end clamp 14, an annular spacing element 58 is mounted on the axle in engagement with the inner race 32a of the end-most ball-bearing unit 32, following which the right-hand end of the axle is inserted through the pivoted member 60 of the clamp which has a hexagonal hole 62 therethrough (Fig. 5) for slidably but non-rotatably receiving the leaf-spring axle. Member 60 of clamp 14 has oppositely disposed recesses 64 therein for reception of the inwardly projecting trunnions 66 on ring part 68 of the clamp which fits within the bore 70 of the clamp body 72 and which is removably held therein by the set screws 16. The clamp body may be secured to any suitable support 74 by screws 76. Inasmuch as member 60 must adjust itself by rotating slightly about the axis of trunnions 66 when the roll axle is being bowed, it is essential that the axle be inserted in the hexagonal hole 62 in member 60 with the flat sides of the axle leaves in general parallelism with the axis of trunnions 66, as shown in Fig. 5. Hence, the right-hand end of the roll axle may be inserted in pivoted member 60 of clamp 14 either before or after the member 60 and ring part 68 are secured in the clamp body 72, and the pivoted member 60 can tilt within ring part 68 about the axis of trunnions 66. A nut 78 on the threaded solid end portion 42 of the axle is adapted to clamp a short spacer element 80 between nut 78 and the outer side of member 60 of the clamp while the earlier mentioned spacing element 58 is clamped between the inner side of clamp member 60 and the inner race of the end-most ball-bearing unit 32, for a purpose which later will appear.

The left-hand end of the axle (Fig. 2) extends through the generally spherical member 82 of clamp 12 with the tube or sleeve 48 having nice sliding fit therein. The clamp member 82 is adjustably seated within the body 84 of the clamp and is held in any position of adjustment by means of the set screws 16. The clamp body 84 may be secured to a suitable support 86 by screws 76.

It is a feature of the invention that the roll 10 may be bowed so as to have any of various amounts of longitudinal curvature, and may be rigidly maintained in any selected bowed condition.

Assuming that the straight roll of Fig. 2 is to be converted to its bowed condition of Fig. 3, the set screws 16 of the end clamp 12 will be loosened, and locking screw 54 will be retracted at the left-hand end of the axle. Also, the nut 78 at the right-hand end of the axle will be loosened to relieve interior elements of the roll of endwise pressure. If the adjusting screw 52 be now screwed inward while screw 54 is held against rotation, the rod or plunger 44 will be forced inward relative to the bifurcated mem-

ber 46 and tube or sleeve 48. Inasmuch as leaf 18 of the leaf-spring axle is rigidly connected to rod or plunger 44, the inward movement of rod or plunger 44 along member 46 shortens the straight line distance between the ends of leaf 18, causing leaf 18 to become bowed. The other leaves of the axle necessarily assume a similar bowed shape because the inner races 32a of the ball-bearing units 32 closely surround all of the leaves and cause them all to bow with bowing of leaf 18, and the leaves can slip relative to each other as may be required to attain any particular amount of curvature for the axle. Preferably, the leaves 18 and 26 and the middle leaf 22 will be somewhat thicker than the other leaves. During the process of introducing bow or curvature in the axle and roll, the tube or sleeve 48 at the left-hand end of the axle can slip as needed in the clamp member 82, in response to bowing of leaf 26 which is connected to the tube or sleeve 48 through the medium of the bifurcated member 46 which is welded at 47 to tube or sleeve 48 and is welded at 49 to leaf 26; and the member 82 can adjust itself as needed within the clamp body 84, assuming that the set screws 16 at clamp 12 are loosened.

As best seen in Fig. 3, the spacing elements 38 are self-adjusting during the bowing process due to an inter-fitting of bevelled ends of adjacent spacing elements 38. One end of the spacing element 38 of each co-acting pair is internally bevelled at 38a and one end of the other element 38 of each co-acting pair is externally bevelled at 38b. These complementary bevelled ends of the spacing elements inter-fit and permit relative adjustment of the inter-fitting ends as the bowing of the axle proceeds, meanwhile maintaining the roll sections 28, 30 in suitably spaced relation.

When the roll has been provided with a predetermined or desired amount of bow or curvature, the locking screw 54 at the left-hand end of the axle will be tightened to lock adjusting screw 52 against accidental turning, and the nut 78 at the right-hand end of the axle will be tightened to put the interior elements of the roll under substantial endwise compression. Finally, the curved roll may be secured with its axis in a desired plane by tightening the set screws 16 of the two end clamps 12, 14.

It will be apparent from the foregoing description, in connection with the drawings, that the roll 10 may be provided with more or less bow to suit any particular sheet-expanding requirements, and the bow or curvature extends substantially the bowing of the leaf-spring axle, and of the roll 10, and desired changes of curvature of the roll may be quickly and easily effected while the roll continues to be supported in its end clamps 12, 14.

Fig. 8 illustrates a modification which, in some respects, is preferred over the structure illustrated in Figs. 1-7. For example, adjustments of the curvature of the roll of the Figs. 1-7 embodiment should be made while the roll is not acting on a travelling sheet. Otherwise, the axle may become deformed to an inoperable extent. The roll of Fig. 8, however, may be adjusted to change its curvature while the roll is operating on a travelling sheet.

In Fig. 8, the end clamps 12, 14 and the roll body structure may be generally the same as

illustrated in Figs. 2 and 3. However, the axle of the Fig. 8 roll has the right-hand end portions of leaves 188, 199, 211, 222, 233, 255 and 266 rigidly secured together with leaves 199 and 211 spaced apart by a short spacer leaf 200' and with leaves 233 and 255 similarly spaced apart by a short spacer leaf 244'. All of the leaves are rigidly secured together throughout their extents inward to a location a little beyond the adjacent end-most ball bearing unit 32, at which location the spacer leaves 200' and 244' terminate. Leaves 199, 211, 233 and 255 extend inward to the left in Fig. 8 throughout the major portion of the extent of the roll, terminating somewhat short of the left-hand end-most bearing unit 32.

The left-hand end portions of leaves 188 and 200 are rigidly secured together with a relatively short spacer leaf 199' spacing leaves 188 and 200 apart and with a short spacer leaf 211' spacing leaves 200 and 222 apart. Similarly, the left-hand end portions of leaves 244 and 266 are rigidly secured together with a short spacer leaf 233' spacing leaves 222 and 244 apart and with a short spacer leaf 255' spacing leaves 244 and 266 apart. The leaves 188, 199', 200 and 211' are rigidly secured together and the leaves 233', 244, 255' and 266 are rigidly secured together, throughout their inward extents to the right in Fig. 8 to a location a little beyond the adjacent end-most bearing unit 32, at which location the spacer leaves 199', 211', 233' and 255' terminate. Leaves 200 and 244 extend inward to the right in Fig. 8 throughout the major portion of the extent of the roll, terminating substantially short of the inner ends of the spacer leaves 200' and 244' at the right-hand end portion of the axle. The left-hand end portion of the middle leaf 222 is free to slip longitudinally between the adjacent spacer leaves 211' and 233'.

The left-hand ends of leaves 188, 199' and 200 extend outward to the left in Fig. 8 beyond the adjacent ends of the other leaves and are rigidly connected to the internally threaded member 444 which may be flattened or otherwise formed for engaging the under side of leaf 200 which is shown welded thereto at 665. The sleeve element 488 fits loosely over the member 444 and the ends of the axle leaves with its inner end engaging the inner race of the adjacent end-most bearing unit 32, and with lower leaf 266 welded or otherwise rigidly secured thereto at 488a. The outer end of sleeve element 488 is closed but has a threaded opening therein for reception of the adjusting screw 522 whose inner end engages the member 444 for forcing the member 444 inward to produce bowing of the axle. A locking screw 544 extends loosely and axially through the adjusting screw 522 and is adapted to be screwed into member 444 to lock the adjusting screw following any adjustment of the latter.

Introduction of curvature, or modification of curvature, in the roll of Fig. 8 may be accomplished in the same manner as described in connection with the roll of Figs. 1-7. However, as earlier mentioned, adjustment of curvature in the roll of Fig. 8 may be accomplished while the roll is operating on a travelling sheet.

Also, in connection with the Fig. 8 embodiment, it should be noted that leaves at the opposite ends of the axle are rigidly secured together to provide a straight portion of axle at each end of the roll. It will be obvious that these straight end sections may be extended to

any desired distance within the roll body to provide a roll having straight end portions of any desired length, in which case all of the variable curvature of the roll would be at the central region of the roll.

The embodiment of the invention illustrated in Fig. 9 is designed to have its opposite end portions identical, with means at each end for adjusting curvature of the roll and with axial clamping means at each end for endwise compression of interior elements of the roll body. Also, each end of the roll of Fig. 9 may be mounted in a similar end-clamp which may be like the end-clamp 12 of the Figs. 1-7 embodiment.

Inasmuch as both ends of the roll of Fig. 9 are identical, and identically mounted, only the left-hand end portion and a central portion of the roll are represented in Fig. 9, and the axle and roll are shown in straight condition prior to introduction of curvature therein.

The illustrated end portion of the axle and roll in Fig. 9 is substantially the same as the corresponding end portion of the axle and roll of the Fig. 8 embodiment. However, the sleeve element 488' which encloses the ends of the axle leaves in Fig. 9 is slidably keyed at 489' against rotation in the part 32 of end clamp 12, and has its inner end exteriorly threaded and provided with a clamping nut 78'. The nut 78' projects inward beyond the inner end of sleeve element 488' and is adapted to engage the outer end of a relatively short sleeve 488'' whose inner end engages the inner ball race of the end-most bearing unit 32.

The illustrated left-hand end of the axle has leaves 188, and 200a rigidly secured together with the relatively short spacer leaf 199' spacing them apart and with spacer leaf 211' spacing leaf 200 from the middle leaf 222, and with the connected ends of leaves 188, 199' and 200a rigidly connected to the internally threaded member 444, as described in connection with Fig. 8. The left-hand ends of leaves 244a and 266 are rigidly connected together with spacer leaves 233' and 255' spacing leaf 244a from middle leaf 222 and spacing leaf 244a from leaf 266, as described in connection with Fig. 8. The lower leaf 266 is welded or otherwise rigidly secured to sleeve element 488' at 488a.

The central portion of the roll of Fig. 9 is provided with a rigid straight portion, indicated by the bracket at B, throughout which portion all of the axle leaves which extend into this central region are rigidly secured together. The axle at this central straight region includes leaves 188, 222 and 266 which extend throughout the length of the roll, and whose ends are free to move relative to each other. Also included at the rigid central region are four relatively long leaves 199b, 211b, 233b and 255b and two short spacer leaves 200b and 244b. The spacer leaves have extent only at the rigid and straight central region, spacer leaf 200b being interposed between leaves 199b and 211b while spacer leaf 244b is interposed between leaves 233b and 255b. Each of leaves 199b, 211b, 233b and 255b has substantial extent from the central straight region both to the left and to the right. Leaf 200a extends inward to the right from the illustrated end of the axle and has substantial engagement between the leaves 199b and 211b, terminating appreciably short of the rigid central region B of the roll. Leaf 244a similarly extends inward to the right between leaves 233b and 255b, terminating at the same location as leaf 200a. The end spacer leaves 199',

200b and 244b are interposed between leaves 199b and 211b, 233b and 255b respectively, and have substantial extent from the central straight region both to the left and to the right. Leaf 200a extends inward to the right from the illustrated end of the axle and has substantial engagement between the leaves 199b and 211b, terminating appreciably short of the rigid central region B of the roll. Leaf 244a similarly extends inward to the right between leaves 233b and 255b, terminating at the same location as leaf 200a. The end spacer leaves 199',

211', 233' and 255' all terminate inwardly appreciably short of the outer ends of leaves 199^b, 211^b, 233^b and 255^b.

Considering that both end portions of the roll of Fig. 9 are constructed and mounted in identical manners, it will be apparent that curvature may be induced in each end portion of the roll, when clamping nuts 78' and locking screws 54 are loosened, by screwing in the adjusting screws 52 at the opposite ends of the roll, while locking screws 54 are held against rotation, followed by screwing in of the locking screws 54, after which interior elements of the roll body will be put under end-wise compression by screwing the clamping nuts 78' toward each other. The end clamp set screws then will be tightened, as described in connection with the Figs. 1-7 embodiment.

The axle of the Fig. 9 embodiment may be provided with a central straight portion B of any desired length. Also, the illustrated relatively short straight end portion of the axle in Fig. 9 may be extended to any desired distance within the opposite ends of the roll body to provide straight end portions of any desired length on the roll body.

It is intended that the patent shall cover, by suitable expression in the appended claims, whatever features of patentable novelty exist in the invention disclosed.

I claim as my invention:

1. An adjustable-curvature roll comprising a roll body, an axle on which said roll body is rotatably mounted, said axle comprising a plurality of superimposed resiliently flexible strips, and said strips having extent within and being relatively slideable within substantial end portions of said roll body whereby the axle is flexible at its portions which extend within said substantial end portions of the roll body, opposite end portions of the axle projecting beyond the roll body at each end of the latter, and said roll body comprising a series of roll sections distributed along said axle and a flexible surface sleeve engaged over all of said roll sections and tying all of said roll sections together for rotation in unison with said surface sleeve, means engaging opposite end portions of said axle and operative to move said end portions of the axle thereby to introduce longitudinal curvature into said substantial end portions of the roll body, and locking means on opposite end portions of said axle and operative at the projecting end portions of the axle for securing the axle in a rigid condition in which it and the roll body thereon have predetermined curvature throughout the extent of said flexible portions of the axle within the roll body.

2. An adjustable-curvature roll comprising a roll body, an axle on which said roll body is rotatably mounted, said axle comprising a plurality of superimposed resiliently flexible strips, and said strips having extent within and being relatively slidably within substantial end portions of said roll body whereby the axle is flexible at its portions which extend within said substantial end portions of the roll body, opposite end portions of the axle projecting beyond the roll body at each end of the latter, and said roll body being flexibly self-adapting for rotation on said axle when said axle is straight and also when said axle has any of various degrees of curvature therein, means on one of said projecting end portions of the axle operable to flex said flexible portions of the axle for introducing varying amounts of curvature into the axle and into said substantial end portions of the roll body thereon, and

means on the opposite projecting end portion of said axle separately operable for securing the axle in a rigid condition with predetermined curvature therein.

- 5   3. A roll comprising a roll body and an axle on which said roll body is rotatably mounted with end portions of the axle projecting at opposite ends of said roll body, said axle comprising a plurality of superimposed relatively long resiliently flexible strips rigidly secured together at one end of the axle, at least two of said strips having extent throughout the extent of said roll body on the axle and being relatively movable within substantial end portions of said roll body, 10 means at the other end of the axle for moving the adjacent ends of said strips toward said secured together ends of the strips thereby to introduce a predetermined amount of curvature into said axle with substantial uniformity of curvature throughout said substantial end portions of the roll body, and means on said other end of the axle for securing said moved ends of the strips against movement relative to said secured together ends thereof whereby said strips become 15 a rigid axle having predetermined curvature at the flexible portions thereof, said roll body being flexibly self-adapting for adopting the general curvature of said axle and being rotatable on the axle regardless of variations in the curvature 20 25 30 of the axle.

4. A roll comprising a roll body having a flexible surface sleeve resiliently engaged over a series of roll sections, an axle on which said roll sections and surface sleeve are mounted for rotation in unison, said axle comprising a long leaf spring having extent throughout the extent of said roll body on the axle whose leaves, at one end of the axle, are rigidly secured together outward of the adjacent end of said roll body, a first member, 35 40 45 at the other end of the axle, rigidly secured to the adjacent end of one leaf of the spring outward of the adjacent end of said roll body, a second member within which said first member is movable, said second member being rigidly connected to the adjacent end of a second one of the leaves of the spring outward of the adjacent end of said roll body, means on the axle for moving said first and second members relatively to effect 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900

by said roll body becomes correspondingly bowed substantially from end to end thereof, and means on the other end of the axle operable for clamping said bearing elements and spacer means together axially of the axle thereby to maintain the axle in a rigid condition with a predetermined amount of bow therein and in the roll body.

6. An adjustable-curvature roll comprising a roll body, a flexible axle on which said roll body is rotatably mounted, said axle comprising a series of resilient flexible strips stacked to constitute a relatively long leaf-spring having its leaves, at one end of the axle, rigidly secured together, at least two of said leaves having extent throughout the extent of said roll body on the axle, and said roll body comprising a series of roll sections slidably mounted in spaced relation on said axle and a flexible surface sleeve resiliently engaged over all of said roll sections tying them together for rotation in unison with said surface sleeve, means on one end of the axle operable for flexing said spring and thereby introducing a predetermined amount of curvature in said roll substantially throughout the extent of said roll body, and locking means at said one end of the axle for securing the axle rigidly in any bowed condition thereof.

7. An adjustable-curvature roll comprising a roll body and a resiliently flexible axle on which said roll body is rotatably mounted, said axle comprising a plurality of resiliently flexible elements rigidly secured together at one end of the axle and free to flex and slip relative to each other throughout the remainder of their extents, at least two of said elements having extent throughout the extent of said roll body on the axle, a plunger rigidly secured to one of said resiliently flexible elements at the other end of the axle, a member slidably supporting said plunger and itself rigidly connected to another one of said resiliently flexible elements, rotatable means on said other end of the axle for effecting a movement of said plunger within said supporting member thereby to effect a bowing of the resiliently flexible element connected to the plunger, there being distributed means along said axle engaging around said resiliently flexible elements whereby the bowing of one of said resiliently flexible elements results in corresponding bowing of the others, and means on said other end of the axle for locking said plunger and its supporting member against relative movement after a predetermined amount of bow has been imparted to the axle and to the roll body thereon.

8. An adjustable-curvature roll comprising a leaf-spring axle, a series of roll sections distributed in spaced relation along said axle, anti-friction bearing units rotatably supporting said roll sections on said axle and themselves slidable on the axle, spacer elements loosely encircling said axle between successive bearing units for maintaining a predetermined spacing of the bearing units, said leaf-spring axle extending beyond each end-most roll section and being flexible throughout said distributed extent of said roll sections on the axle, means at one end of the axle for imparting a predetermined amount of bow to the axle substantially throughout the extent thereof while said spacer elements are free of any substantial end-wise compression, and means on the other end of the axle for subjecting said spacer elements to substantial end-wise compression following bowing of the axle thereby to impart rigidity to said axle and roll in any bowed condition thereof.

9. An adjustable-curvature roll having a flexible roll body, an axle supporting said roll body and comprising a series of superimposed resiliently flexible flat strips rigidly secured together throughout one substantial portion of the length of the axle thereby to provide a straight rigid section of axle, at least some of said strips having flexible extent from said straight rigid section throughout substantial end portions of the extent of said roll body on the axle and projecting beyond the roll body at opposite ends thereof, means at spaced locations within the roll body maintaining the flexible portions of superimposed strips against spreading apart while permitting relative longitudinal slip thereof, and a manually operable clamp on one end of the axle for engaging an end portion of a said strip and forcing it toward said straight rigid section of the axle thereby to introduce curvature in said axle between said straight section and said manually operable clamp, portions of said flexible roll body on said curved portions of said axle acquiring a generally corresponding curvature.

10. An adjustable-curvature roll having a flexible roll body, an axle supporting said roll body and comprising a series of superimposed resiliently flexible flat strips of which some strips have extent throughout the length of the roll body and project at opposite ends of the roll body, means rigidly securing together at least a plurality of the projecting end portions of strips at each end of the axle substantially throughout the length of their mutual projection beyond the roll body thereby to provide a substantially rigid and straight projecting section of axle at each end of the roll body, means rigidly securing together all of the strips which are superimposed in another section of the axle which is within said roll body, thereby to provide a straight and rigid section of axle within the roll body on which the roll body is maintained straight, and mechanism manually operable on one end of the axle for forcing said straight and rigid sections of axle relatively toward each other to introduce curvature in the intervening portions of the axle and in the portions of the roll body thereon.

11. An adjustable-curvature roll comprising a series of resiliently flexible generally flat strips stacked to provide a long leaf spring axle, a roll body comprising a multiplicity of roll sections slidably and rotatably mounted on said axle in slightly spaced relation with a flexible surface sleeve engaged over all of said roll sections and tying them together for rotation in unison with said sleeve, spacer elements slidably and rotatably mounted on said axle for maintaining said roll sections in spaced relation when said spacer elements are subjected to endwise compression, means rigidly securing together leaves of the axle throughout one substantial portion of the length of the axle thereby to provide a straight rigid axle section of substantial length, means on the axle remote from said straight rigid section of the axle operative to effect relative movement of leaves of the axle between said straight rigid axle section and said remote means, thereby to impart a predetermined amount of curvature to said axle, and the roll body thereon, at regions of the axle and roll body located between said straight rigid axle section and said remote means, and abutment means on opposite end portions of said axle operable relatively toward each other along the axle for clamping said roll sections and spacer elements together longitudinally of said roll body.

12. An adjustable-curvature roll comprising an axle, and a flexible roll body rotatably mounted on the axle, said axle having a series of resiliently flexible strips therein of which at least one strip is longer than said roll body and projects beyond the roll body at the opposite ends thereof, means within and at spaced locations along said roll body maintaining said flexible strips against spreading apart but permitting relative longitudinal slip between some of the strips throughout at least a substantial portion of their extents within the roll body, means rigidly securing together all of the said strips which have extent through one substantial portion of the length of the axle thereby to provide a substantial rigid and straight section of axle, and mechanism manually operable on at least one of said projecting ends of said strip which is longer than the roll body for effecting relative movement of the projecting ends of said strip which is longer than the roll body toward each other thereby to flex and provide curvature in said axle and flexible roll body throughout those portions of the roll body which are supported on flexible portions of said axle.

13. An adjustable-curvature roll having a flexible roll body, an axle supporting said roll body and comprising a series of superimposed resiliently flexible flat strips, means rigidly connecting together all of the strips throughout one substantial portion of their mutual extent within the roll body thereby to provide a straight and rigid axle section on which a section of the roll body is maintained straight, there being a plurality of said strips extending flexibly from said straight and rigid section of the axle toward opposite ends of the axle, means at spaced locations within the roll body maintaining said flexible portions of the strips against spreading apart while permitting relative longitudinal slip therebetween, and mechanism on each end of the axle manually operable to impart curvature to the axle at opposite sides of said rigid and straight section thereof, and to the portions of the roll which are supported on the flexible portions of the axle.

14. An adjustable-curvature roll having a flexible roll body, an axle supporting said roll body and comprising a series of superimposed resiliently flexible flat strips, means rigidly connecting together all of the strips throughout one sub-

stantial portion of their mutual extent within the roll body thereby to provide a straight and rigid axle section on which a section of the roll body is maintained straight, there being a plurality of said strips extending flexibly from said straight and rigid section of the axle toward opposite ends of the axle, means at spaced locations within the roll body maintaining said flexible portions of the strips against spreading apart while permitting relative longitudinal slip therebetween, mechanism on each end of the axle separately operable to impart curvature to the axle, and to the roll body thereon, at opposite sides of said rigid and straight section of the axle, and coacting clamping means on opposite end portions of the axle for subjecting the roll body to endwise compression following introduction of curvature in the axle and roll body.

15. A roll comprising a roll body having a flexible surface sleeve resiliently engaged over a series of roll sections, an axle on which said roll sections and surface sleeve are rotatable in unison, said axle comprising a long leaf spring whose leaves, at one location, are rigidly secured together, a first member rigidly secured to an end portion of one of the leaves of the spring in substantially spaced relation to said location, a second member rigidly secured to an end portion of another one of the leaves of the spring, said first and second members being at the same end of the roll, means on the axle for moving said first and second members relatively in directions longitudinally of the roll for bowing said spring-axe between said location and the latter said means, and manually operable means on the axle for locking said first and second members against relative movement.
